UNITED STATES PATENT OFFICE.

BERTHA CRONENBERG, OF BUFFALO, NEW YORK, ASSIGNOR TO MORRIS BERNHARD, OF SAME PLACE.

DESIGN FOR A PORTIÈRE-ROPE.

SPECIFICATION forming part of Design No. 24,581, dated August 6, 1895.

Application filed June 17, 1895. Serial No. 558,139. Term of patent 7 years.

To all whom it may concern:

Be it known that I, BERTHA CRONENBERG, a citizen of the United States, residing at the city of Buffalo, in the county of Erie and State of New York, have invented and produced a new and original Design for Portière-Ropes, of which the following is a specification.

This design relates to the ornamentation of ropes used for ornamental purposes, such as the cords of rope portières, rope valances, curtain loops and holders, &c.

This design is illustrated in the accompanying drawing, which forms part of this specification, and represents a fragmentary elevation of such a rope.

The leading feature of my design consists of a strand of loops arranged spirally around a core or inner cord, with its convolutions separated and exposing the underlying core or cord between the convolutions.

A represents the core or inner cord, which is substantially of uniform diameter throughout, and B represents the strand of looped material—such, for instance, as uncut chenille—

which is wound spirally around the core or rope, with the convolutions of the spirally-arranged strand separated by an intervening spiral space c, through which the core or cord is exposed. The convolutions of the looped material are raised above or project beyond the surface of the rope around which they are coiled, and as they are separated from each other they expose the core, which is of less diameter, so that the surface of the ornamental rope is made up of alternating spiral projections and depressions. This imparts to the rope a rich ornamental appearance, which can be increased by contrasting the alternately raised and depressed portions in color.

What I claim is—

The design for a portière rope, substantially as herein shown and described.

Witness my hand this 15th day of June, 1895.

BERTHA CRONENBERG.
